Inventor,

Ira S. Barnett

By C. J. Stockman Atty.

UNITED STATES PATENT OFFICE.

IRA S. BARNETT, OF LOUISVILLE, KENTUCKY.

DESIGN FOR A SMOKER'S PIPE.

60,505.

Specification for Design.

Patented Mar. 7, 1922.

Application filed May 31, 1921. Serial No. 473,916. Term of patent 14 years.

To all whom it may concern:

Be it known that I, IRA S. BARNETT, a citizen of the United States, residing at Louisville, county of Jefferson, and State of Kentucky, have invented a new, original, and ornamental Design for a Smoker's Pipe, of which the following is a specification, reference being had to the accompanying drawing, forming part thereof.

Fig. 1 is a side elevation of a pipe embodying my invention.

Fig. 2 is a plan view thereof.

I claim:

The ornamental design for a smoker's pipe substantially as shown.

IRA S. BARNETT.
